UNITED STATES PATENT OFFICE.

CHARLES C. JESSEN, OF WILMINGTON, DELAWARE, ASSIGNOR TO ATLAS POWDER COMPANY, OF WILMINGTON, DELAWARE, A CORPORATION OF DELAWARE.

SPINNING MACHINE.

Application filed February 5, 1925. Serial No. 7,069.

This invention relates to spinning machines. It is common, in the art of spinning artificial silk from cellulose solutions, to discharge the cellulose solution from spin-
5 narettes into an alkaline bath and to lead the threads which are "set" or solidified by said bath over suitable guiding elements and to centrifuges where the plurality of threads discharged from the spinnarettes are twisted
10 together by the action of the centrifuges.

It is a primary object of the present invention to provide a new and improved assemblage of parts adapted to carry out the above named functions in a facile and effi-
15 cient way.

A further object of the invention is to provide an improved motor mounting for the motors which drive the centrifuges.

A further object of the invention is to
20 provide an improved means for rendering said motors self-oiling.

Further objects and advantages of the invention will be set forth in the detailed description which follows.

25 In the accompanying drawings:

Figure 1 is an end elevation of a spinning machine constructed in accordance with the present invention with parts in section and other parts broken away to preserve the clearness of the drawing.

Figure 2 is a plan view of a portion of the spinning machine with parts omitted.

Figure 3 is a transverse sectional view through the spinning machine with the parts at the far end of the machine omitted.

Figure 4 is a partial side elevation of the machine illustrating two of the spinning units and the driving mechanism of varying parts.

40 Figure 5 is a detail sectional view through one of the motors of the centrifuges, illustrating a novel lubricating means for the same.

Figure 6 is a detail view partly in elevation and partly in section, illustrating the lower portion of one of the centrifuges, a driving motor, and the connection between the same; and

50 Figure 7 is a sectional view through one of the guide tubes, hereinafter described.

Like numerals designate corresponding parts in all of the figures of the drawing.

Referring now to the drawings, 5 designates the base portion of a frame which includes longitudinally extending angle irons

6. Standards 7, supported upon the base frame 5, serve, in turn, to support the superstructure hereinafter described. A tank 8 is disposed centrally of the machine and inside of the line of centrifuges constituting 60 the spinning units. This tank is adapted to receive a suitable solution which varies according to the particular spinning process employed. In the case of the "copper-ammonia process" the tank receives an alkaline 65 bath, such for example, as caustic soda, into which the cellulose solution is discharged through a number of very minute openings formed in the spinnarettes 10. These spinnarettes are carried by tubular arms 11 70 which are of a usual and well known construction and receive their supply of the cellulose solution through pipes 12 and flexible connections 13. These connections and the rotary feed pumps for the solution, indicated at 14, are also of a usual and known construction. The pumps are driven by gears, indicated at 15 and 16, from longitudinally extending shafts 17. The main drive shaft of the machine is indicated at 80 18. This shaft carries a driving pulley 19 and an elongated pinion 20. A large gear wheel 21 which meshes with the pinion 20 is mounted upon a shaft 22 and this shaft 22, in turn, carries a gear wheel 23 which 85 meshes with a gear wheel 24, upon the shaft 25. The gear wheels 23 and 24 are of the same size and mesh with gear wheels 26 and 27. The gear wheels 26 and 27 have smaller gear wheels 28 and 29 affixed to them to turn 90 with them and gears 26 and 28 and 27 and 29 are respectively mounted upon stub shafts 30 and 31 mounted in slots 32 of movable brackets 33. The position of the brackets themselves, may be adjusted, since 95 they are pivoted to move about the axes constituted by shafts 17 and are provided with arcuate extensions 34, having arcuate slots 35 formed therein for the passage of suitable binding elements 36, which project 100 from the eyes 37, of fixed brackets 38. Only the left hand bracket 33 has been illustrated, the right hand bracket 33 has been omitted to more clearly show the bracket 38 lying behind the same. The gear wheels 28 and 105 29 mesh with gear wheels 39 and 40 on the shafts 17.

The reason for mounting the stub shafts 30 and 31 in adjustable brackets, such as 33, is to permit of the substitution of gears of 110

another size at this point, when desired, to thereby vary the discharge rate of the metering feed pumps 14. It is common practice and merely a matter of mechanical skill 5 to mount gears in this fashion and for the purpose indicated, construction of this sort being common in lathes and many other mechanical devices. The elongated pinion 20 (Figure 4) also meshes with a gear wheel 10 (Figure 4) also meshes with a gear wheel 42 upon a horizontal shaft 41. The shaft 42 carries a bevel pinion 43 which meshes with a bevel pinion 44 on the lower end of an upright shaft 45. Beveled pinions 46 and 15 47 transmit motion from the shaft 45, to a horizontal shaft 48. This shaft carries a gear wheel 49 (Figure 1) and a pinion 50. The pinion 50 meshes with a gear wheel 51, upon a longitudinally extending cam shaft 20 52, while the gear wheel 49 meshes with a gear wheel 53 upon a longitudinally extending shaft 54 constituting one of the godet wheel drive shafts. The other godet wheel drive shaft 55 is driven by a gear wheel 56 and an interposed idler gear 57 from the 25 gear wheel 49.

The godet wheel drive shafts 54 and 55 carry beveled pinions 56' and 57', which mesh with beveled pinions 58 and 59 upon the obliquely disposed godet wheel shafts 30 61. The latter shafts are mounted in bearing brackets 62, which are in turn clamped by bolts 63 to longitudinally extending channel irons 64 that are supported upon the standards 7. Only one of the standards 7 35 has been illustrated, but it is to be understood that as many of these standards will be employed as the length of the machine may justify. It will be noted that the machine comprises a large number of spinning 40 units, some of which are disposed upon one side of the machine and some of which are disposed upon the other side of the machine, and there may be as many of these combined in a single machine, as is desired.

45 Each spinning unit comprises a centrifuge, and since they are all alike a description of one will serve as a description of all. Each centrifuge comprises a rotative bowl or pot 66, the base of which, indicated at 67, has 50 frictional engagement with a disc 68 to which rotation, at high speed, is imparted by an electric motor 69. The several centrifuges are mounted in longitudinally extending housings 70.

55 The plurality of threads discharged in parallel from the orifices of the spinnarettes are led, in their parallel relation, over the godet wheels indicated at 71, and thence to the guide tubes 72, to which vertical reciprocation is imparted by traverse rods 73. These traverse rods pass through guides 74 of the brackets 62 and have vertical reciprocation imparted to them by rock arms 75. These rock arms are pivoted at 76 and their 60 outer ends have pivotal engagement with

the caps 77 upon the upper ends of the traverse rods.

The necessary upward movement is imparted to the traverse rods by cams 78 of cam shaft 52, said cams acting against the tails 79 of the rock arms 75.

The action of the centrifuges in twisting the threads together is well known in the art and is not peculiar to this invention. It suffices to say that the thread passing through the guide tubes 72 is thrown outwardly by centrifugal force and against the walls of the pots 66 and that the action of the pots in carrying the thread around at a high rate of speed results in twisting the threads together about the axis constituted by the center line of the guide tubes. One of the guide tubes is illustrated upon an enlarged scale in Figure 7. These tubes are of substantially the same construction as those heretofore employed except that from the lower-most restricted portion of the tube, indicated at Figure 8, the tube flares outwardly in bell formation at 81 upon a gradual curve, so that the thread is, at no time, 90 bent to a sharp angle but leaves the tube at such angle that damage to the tender threads is eliminated.

The pots 66 have small openings 66a formed in them through which the caustic soda, or like solution, may be thrown from the pots by centrifugal force into the housings 70 from which it is conducted by means of ducts 82 to a collecting tank 83, see Figure 3. 100

An overflow pipe 84 serves to maintain the solution in tank 8 at a determined level, said overflow pipe discharging into collecting tank 83.

While the tank 8 extends the full length 105 of the machine, the several spinnarettes may be disposed in more or less individual compartments of said tank, by placing partitions 8a (Figure 4) across the tank at intervals and between the spinnarettes. These partitions may extend the full height of the tank or may terminate short of the bottom thereof to permit a single supply pipe, and a single overflow pipe, to take care of the alkaline solution for the whole tank. I contemplate 110 employing either of these constructions as may be desired. The several motors 69 are supported upon channel irons 85, which are in turn supported by brackets 86 of the frame 5 and these channel irons preferably 115 carry housings 87, enclosing the lower portions of the motors and the current carrying wires for the same. As indicative of that fact, I have illustrated an insulating member 88 of conventional form in Figure 120 6, the conductors being indicated at 89. The housings are also utilized as air ducts through which fresh air may be blown to cool the motors. To this end the lower portions 125 of the motor casings are provided with 130

suitable openings 69^b through which the air may pass as indicated by the arrows Z, upwardly around the stators and between the stators and rotors of the motors. Drop doors 87^a are disposed at intervals along the housings to facilitate access to the wiring. The drive between the motor 69 and the pot 66 (see Figure 6) consists of a shaft comprising the sections 90 and 91 which are united by a universal joint 92. This universal joint may be of any desired construction. In the present instance it comprises a pair of yokes 93, 94, which are secured to a flexible disc 95. This is a known form of universal joint and any known form of universal joint may be substituted therefor. The upper shaft section 91 is pinned to a sleeve 92'. A collar 93' has a press fit upon this sleeve as does the inner member 94' of an anti-friction bearing, which includes the balls or rollers 95' and the outer race 96, the latter having a press fit in a cylinder 97. The lower end of the cylinder 97 is closed by a cap 98 and the interior of the cylinder constitutes an oil chamber. A frusto-conical cylinder 99, is carried by a collar 100, which has a press fit on the sleeve 92'. Openings 101 are formed through this collar adjacent the inner face of the cylinder, these openings terminating adjacent the anti-friction elements 95'. Thus, since cylinder 99 will rotate at a high rate of speed, it follows that the inclination of its walls will cause the oil to travel upwardly therealong, due to the fact that the oil is being thrown outwardly by centrifugal force. The oil that travels upwardly along the inner walls of the cylinder passes through the openings 101 and thus the anti-friction bearings are kept oiled without any attention whatever.

The cylinder 97 is preferably supported upon a block of rubber 102. The inner face of the race way 96 is formed upon an arc struck from the center of the shaft section 91. Thus the motor drive is cushioned by the block 102 and is prevented from any possibility of binding by the provision of the universal joint and type of ball-bearing shown.

In Figure 5 I have illustrated means for lubricating the upper bearings of the vertically disposed motors. As far as the electrical features of these motors are concerned, they are of conventional construction. However, in order to insure perfect lubrication, particularly, of the upper bearings, I bore the motor shafts 69^a longitudinally, as indicated at 110. An oil well 111 is formed in a cap 112, adapted to be screwed in the lower end of the motor casing 113. The lower end of the shaft 69^a is supported upon a thrust bearing 114 of conventional form and the upper end of the shaft has its bearing in a bushing 115 of any suitable metal. A tube 116 depends into the oil well 111 and its length includes an outwardly flaring, inverted, frusto-conical portion 117. Since the shaft 69^a and the tube 116 rotate at a high rate of speed it follows that the oil within the tube and shaft will be thrown outwardly by centrifugal force and the shape of the part 117 is such as to induce an upward flow of the oil through the bore 110 of shaft 69^a. At its upper end this bore is in communication through a transverse port 118 with a spiral groove 119 formed in the outer face of the shaft, which groove leads the oil up to the top of and along the whole length of the bearing sleeve 115. The lower bearing 120 as well as the thrust bearing 114, are sufficiently lubricated by being disposed in the oil chamber 121. However, the lower bearing may be lubricated in the same manner that the upper bearing is lubricated by forming a spiral groove 119^a about the motor shaft, opposite the lower bearing 120 and connecting said groove by a port 119^b with the bore 110 of the shaft, at a point beneath a baffle plate 119^c.

Any oil which finds its way down the outside of the shaft 69^a from groove 119 enters the cup 122 which is secured to and rotates with the shaft 69^a and when enough oil has been collected in this cup it is thrown outwardly by centrifugal force from the upper edge of the cup at 123 and finds its way back into the oil chamber 121 through conduits 124 and 125.

It is to be understood that the invention is not limited to the precise construction set forth but that it includes within its purview whatever changes fairly come within either the terms or the spirit of the appended claims.

Having described my invention what I claim is:

1. A machine of the character described comprising a tank adapted to hold a bath, a spinnarette discharging thereinto, a godet wheel located thereabove, a centrifuge, traverse rods constituting part of the guiding means for the threads from the godet wheels to the centrifuges, and means for imparting vertical reciprocation to the traverse rods comprising a bell crank lever consisting of a long arm and a short arm, the long arm being engaged with the traverse rods, a cam shaft, and a cam on said shaft acting against the short arm of said lever.
2. A machine of the character described comprising a supporting frame, a centrally arranged tank therein, a plurality of substantially longitudinally aligned centrifuges upon the opposite sides of the frame and outwardly of the tank, a main driving shaft, a pair of pump shafts, driving gearing between the main driving shaft and the pump shafts, a spinnarette for each centrifuge, pumps operated from the pump shafts and discharging solution through said spinna-

rettes into said tank, a plurality of godet wheels arranged above the centrifuges for conducting the spun threads from the spinnarettes to the centrifuges, angularly disposed shafts upon which the godet wheels are mounted, longitudinally extending shafts for driving the godet wheels, gearing between the longitudinally extending shafts and the shafts of the godet wheels, means for driving the longitudinally extending shafts from the main drive shaft, a longitudinally extending cam shaft, means for driving the cam shaft from the main drive shaft, cams upon the cam shaft, bell crank rock levers pivoted at their heels and comprising long arms and short arms, said cams acting against said short arms, vertically disposed traverse rods with which the long arms of the said levers are engaged, and guide tubes carried by and vertically movable with the traverse arms and acting to guide the spun threads into the centrifuges.

3. In a machine for spinning artificial silk, the combination with a supporting frame, a tank for receiving a bath into which the cellulose solution is discharged

through the spinnarettes said tank being disposed substantially centrally of the machine and extending longitudinally thereof, a plurality of vertically disposed, centrifugal spinning devices disposed in substantially longitudinal alignment upon the opposite sides of the machine and outwardly of said tank, overhead guiding elements for conducting the threads from the spinnarettes to said centrifugal devices, guide tubes for the threads, disposed vertically in the centrifugal devices, vertically disposed traverse rods by which said tubes are carried, overhead horizontal cam shafts extending longitudinally of the machine, cams carried thereby and the bell crank levers arranged in pairs, one upon each side of each cam, said levers comprising long arms and short arms, the short arms bearing against the peripheries of the respective cams and the extremities of the long arms being engaged with said traverse rods.

In testimony whereof he affixes his signature.

CHARLES C. JESSEN.
